(57) **CLAIM**

The ornamental design for a hard hat, as shown and described.

DESCRIPTION

FIG. 1 is a top perspective view of a hard hat showing our new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines illustrate environmental features that form no part of the claimed design.
